UNITED STATES PATENT OFFICE.

WILLIAM J. RAY, OF LOUISVILLE, KENTUCKY, ASSIGNOR OF ONE-HALF TO THOMAS P. RAY, OF KENILWORTH, ILLINOIS.

PLASTERING-MACHINE.

1,040,253.

Specification of Letters Patent.

Patented Oct. 1, 1912.

Application filed January 31, 1912. Serial No. 674,534.

To all whom it may concern:

Be it known that I, WILLIAM J. RAY, a citizen of the United States, residing at Louisville, in the county of Jefferson and State of Kentucky, have invented new and useful Improvements in Plastering-Machines, of which the following is a specification.

The present invention relates to plastering machines, and the primary object is to provide novel, simple and effective means that will apply plaster to walls, the same operating with speed and accuracy, and being adjustable to the work to be performed.

A simple embodiment of the invention that has proven entirely practicable, is illustrated in the accompanying drawings, wherein:

Figure 1 is a rear elevation of the machine. Fig. 2 is a front elevation, showing the machine on a supplemental support. Fig. 3 is a plan view. Fig. 4 is a sectional view on the line 4—4 of Fig. 3. Fig. 5 is a detail view illustrating a floater for use in connection with the machine. Fig. 6 is an end view of the machine. Fig. 7 is a sectional view on the line 7—7 of Fig. 3.

Similar reference numerals designate corresponding parts in all the figures of the drawings.

In the embodiment disclosed, a supporting frame is employed, comprising a base 7, on which are mounted corner standards 8, these standards being preferably made of wooden strips 9, against the inner faces of which are fastened channel irons 10. The upper ends of the standards are connected by longitudinal and transverse bars 11. The said channel irons 10 constitute guides for a vertically movable carriage that is in the form of an open frame 12, having shoes 13 that operate in said channel irons 10. The carriage, in turn, constitutes a support and guide for a horizontally movable carrier, designated as a whole by the reference numeral 14.

For the purpose of supporting and moving the carriage 12, vertical screws 15 are journaled in the ends of the supporting frame, and boxes 16, secured to the ends of said carriage, have threaded engagements with these screws. The lower ends of the screws carry beveled gear wheels 17, meshing with corresponding wheels 18 on the ends of a shaft 19 journaled on the base of

the supporting frame in suitable boxes 20. A transversely disposed driving shaft 21, journaled on the base, is provided at its inner end with a gear wheel 22, and feathered on the shaft 19, is a pair of oppositely disposed beveled gears 23 movable longitudinally of the shaft 19 and actuated by any suitable means, as for instance, a lever 24. By shifting the wheels 23, either may be brought into mesh with the wheel 22, and thus the screws 15 can be rotated in opposite directions for raising and lowering the carriage. When the wheels 23 are in an intermediate position, neither is in mesh with the wheel 22, so that said carriage will be at a standstill, and can thus be maintained in any desired adjusted position. It will be understood that the driving shaft 21 can be operated from any suitable source of power, a coupling 25 being shown at the outer end of the same.

The carrier 14, as already stated, reciprocates horizontally in the carriage 12, and it is moved by means of a pair of horizontally disposed screws 26 journaled on the carriage and having threaded engagements with boxes 27 secured to the under side of the carrier. The screws 26, at one end, are connected by a sprocket chain 28 passing about sprocket wheels 29, fixed to said screws. The other ends of these screws, have loosely journaled thereon, sprocket wheels 30, around one of which passes a sprocket chain 31, that also engages the other and is so disposed as to cause said wheels to rotate in opposite directions. Clutch devices 32 of any suitable character are mounted on the screws 26, and are connected to a lever 33, pivoted at its center, as shown at 34, and so arranged that either sprocket wheel 30 can be clutched to its screw, while the other remains unclutched. These clutch devices 32 are of course fixed to rotate with the screws, but are movable along said screws to alternately lock the sprocket wheels 30 to their respective screws. The sprocket chain 31 passes about a third sprocket wheel 35, mounted on a second driving shaft 36, journaled longitudinally upon the carriage, and the sprocket wheel 35 can be clutched to and unclutched from this shaft 36 by an ordinary clutch member 37, actuated by a lever 38.

The shaft 36 is provided at one end with a beveled gear wheel 39, in mesh with an

other wheel 40 that is feathered on a vertical countershaft 41 journaled on one corner of the supporting frame. The wheel 40 is caused to move up and down with the carriage, by means of a bracket 42 engaged therewith and mounted on said carriage. The vertical counter-shaft 41 has a beveled gear connection 43 at its lower end, with a stub shaft 44 geared to the main driving shaft 21, as illustrated at 45, the gear on the driving shaft 21 having a clutch connection therewith, as illustrated at 46.

The carrier 14, as illustrated more particularly in Fig. 4, comprises a plaster receptacle or hopper 47, having an outlet opening 48 in one end, in which opening is journaled a rotary spout 49, terminating in a flared plaster delivery nozzle 50. This nozzle has a plurality of radial blades 51 and a central head 52 that is detachably connected to the shaft 53 of a spiral conveyer 54, extending through the lower portion of the receptacle 47. It will be noted that the screw of this conveyer diminishes in its pitch toward the delivery spout. The rear end of the conveyer shaft 53 projects through the rear end of the receptacle 47, and is provided with a gear wheel 55 meshing with a gear wheel 56 that is feathered on the shaft 36, so as to move along said shaft with the carrier. A slide 57 is movable across the receptacle or hopper 47, just above the conveyer for the purpose of cutting off the feed of material whenever desired.

A scraper plate 59 is associated with the spout 50, and is mounted, by means of a plurality of arms 58, on a gear wheel 72 journaled on the neck of said spout and meshing with a pinion 71 fixed to the adjacent end of a shaft 70 journaled in the carrier alongside the hopper and having a hand-operating wheel 69 attached to its rear end.

It will be noted that the supporting frame is journaled on casters 60, so that it may be readily moved in any direction, and it is properly positioned with respect to the wall to be plastered by gages, shown in the form of bars 61, slidably mounted in guides 62, and carrying rollers 63. These gages are held by suitable set screws 64.

Briefly described, the operation of the apparatus is as follows. The supporting frame is properly located, so that the nozzle 50 will be adjacent to the wall to be plastered. The plaster is then introduced into the hopper or receptacle 47, and rotary motion is imparted to the drive shaft 21. It will be evident therefore that by connecting and disconnecting the screws 15, the carriage may be raised or lowered, and stopped, or can be moved alternately in opposite directions, that is, toward either end of the frame, as desired. In like manner, by connecting and disconnecting either of the sprocket wheels 30 to the horizontal screws 26, the carrier

can be moved back and forth in a horizontal direction. The nozzle 50 can therefore be made to traverse the wall in any direction desired, and the plaster will be moved by the conveyer to said nozzle, where it will be delivered against the wall, the blades properly depositing the same. This conveyer is driven from the main shaft through the medium of the shaft 41, the gears 39 and 40, the shaft 36 and the gears 55 and 56, so that said conveyer will be rotated irrespective of the position of the receptacle or hopper 47. Moreover, it will be evident that inasmuch as the conveyer shaft 53 is connected to the central head 52 of the nozzle, said nozzle with its blades, will be rotated, for the blades are rigidly connected to the nozzle. The scraper plate 59 can be employed for floating and can be moved to various positions, as will be evident by operating the hand wheel 69. Or if it is desired to float the plaster, after its application, the floater 50^a, shown in Fig. 5, may be employed. This floater is attached to a flexible shaft 53^a, driven by the motor or engine and held in position by hand. This floater 50^a is used in finishing. In case a high wall is to be operated upon that will not be reached by the ordinary machine, the supporting frame can be placed on a vertically movable platform, shown in Fig. 2, and designated 65. This platform is mounted on vertical screws 66, operated by a horizontal shaft 67, geared thereto, as illustrated at 68.

From the foregoing, it is thought that the construction, operation and many advantages of the herein described invention will be apparent to those skilled in the art, without further description, and it will be understood that various changes in the size, shape, proportion, and minor details of construction, may be resorted to without departing from the spirit or sacrificing any of the advantages of the herein described invention.

Having thus fully described my invention, what I claim as new, and desire to secure by Letters Patent, is:

1. In a plastering machine, a supporting frame, a carriage vertically movable thereon in one direction, a carrier movable on the carriage in another direction, plastering mechanism mounted on the carrier, driving means mounted on the supporting frame, and automatic operating means for the plastering mechanism actuated by the driving means and effecting the movement of said plastering mechanism irrespective of the position of the carrier.

2. In a plastering machine, the combination with a support, of a carriage movable thereon in one direction, a carrier movable on the carriage in another direction, driving means mounted on the support, automatic mechanism actuated by said driving means

for effecting the movement of the carriage and also the movement of the carrier, plastering mechanism mounted on the carrier, and operating means for the plastering mechanism driven by the driving means irrespective of the position of said plastering mechanism.

3. In a plastering machine, a supporting frame, a carriage movable thereon, a screw journaled in the carriage, a carrier movably mounted on the carriage and engaged with the screw, means mounted on the frame for driving the screw and plastering mechanism mounted on the carrier.

15 4. In a plastering machine, a supporting frame, a carriage mounted thereon, screws journaled in the carriage, oppositely driven wheels rotatable with respect to the screws, means for clutching either wheel to one of 20 the screws, a carrier having a threaded engagement with the screws, and plastering mechanism mounted on the carrier.

5. In a plastering machine, a supporting frame, a carriage movably mounted thereon, 25 screws journaled in the carriage, gearing connecting the screws for moving them simultaneously in the same direction, oppositely revolving wheels loosely mounted on the screws, means for driving the wheels, 30 means for clutching either wheel to its screw, a carrier having threaded engagements with the screws, and plastering mechanism mounted on the carrier.

6. In a plastering machine, a supporting frame, a vertically movable carriage mounted thereon, means for moving the carriage vertically, a driving shaft on the frame, a driving shaft on the carriage, gearing connecting the shafts and permitting the movement of the carriage, screws on the carriage, a sprocket chain connecting the screws for insuring their simultaneous movement in the same direction, sprocket wheels loosely journaled on the screws, clutch devices for alternately connecting the sprocket wheels to their respective screws, a sprocket chain driven by the shaft on the carriage and engaging the sprocket wheels to rotate the same in opposite directions, a carrier movable on the carriage and having threaded engagements with the screws, and plastering mechanism mounted on the carrier.

7. In a plastering machine, the combination with a supporting frame, of a carriage vertically movable therein, screws journaled in the supporting frame and having threaded engagements with the carriage, a driving shaft, gear connections between the driving shaft and screws for rotating the same in opposite directions to raise and lower the carriage, a carrier slidably mounted on the carriage, screws journaled in the carriage and having threaded engagements with the carrier, gearing connecting the driving shaft and carriage, means for rotating the latter

screws in either of opposite directions and simultaneously in the same direction, and plastering mechanism mounted on the carrier.

8. In a plastering machine, the combination with a movable supporting frame, of a drive shaft journaled thereon, vertical screws journaled in the supporting frame, a vertically movable carriage slidably mounted in the supporting frame and having threaded engagements with the screws, gearing connecting the driving shaft and screws for rotating the same in opposite directions, a counter-shaft journaled on the frame and driven by the driving shaft, a second driving shaft journaled on the carriage, gearing connecting the counter-shaft and second driving shaft, screws journaled in the carriage, gearing connecting the second driving shaft and screws for rotating the same in either of opposite directions and simultaneously in the same direction, a horizontally movable carrier slidably mounted on the carriage and having threaded engagements with the screws thereof, and plastering mechanism mounted on the carrier.

9. In a plastering machine, the combination with movable carrying means, of a plaster delivery hopper, a nozzle rotatable with respect to the hopper, and a conveyer for delivering plaster from the hopper to the nozzle.

10. In a plastering machine, the combination with movable carrying means, of a plaster delivery nozzle, a plaster receptacle, a spout connecting the receptacle and nozzle, and permitting the rotation of the nozzle with respect to the receptacle and a conveyer for delivering plaster through the spout to the nozzle.

11. In a plastering machine, the combination with movable carrying means, of a plaster receptacle, a delivery nozzle communicating with the receptacle, blades carried by the nozzle, means for delivering plaster from the receptacle to the nozzle, and a scraper associated with the nozzle.

12. In a plastering machine, the combination with movable carrying means, of a plaster receptacle, a rotary plaster delivering nozzle communicating with the receptacle, and a rotatable scraper carried by the nozzle and having a path of movement outside of the same.

13. In a plastering machine, the combination with movable carrying means, of a plaster receptacle mounted thereon, a rotary screw conveyer operating in the receptacle, a delivery nozzle connected to the conveyer and rotatable therewith, blades arranged in the nozzle, and a rotatable scraper operating around the nozzle.

14. In a plastering machine, the combination with a supporting frame, of a vertically movable carriage mounted thereon,

- means for reciprocating the carriage, a horizontally movable carrier mounted on the carriage, means for reciprocating the carrier, a plaster receptacle mounted on the carrier,
- 5 a rotary delivery nozzle journaled on the receptacle, a screw conveyer operating in the receptacle and connected to the nozzle, and means for operating the conveyer and rotating the nozzle.
- 10 15. In a plastering machine, the combination with movable carrying means, of a plaster receptacle mounted thereon, means for delivering plaster from the receptacle, said means projecting from one side of the carrying means, and an adjustable gage mounted on the carrying means and projecting from the same side as the delivery means.
- 15 16. In a plastering machine, the combination with movable carrying means, of means for delivering plaster mounted thereon, a support rotatable upon the delivering means, a scraper carried by the rotatable support, and means for rotating said support.
- 20 17. In a plastering machine, the combination with movable carrying means, of a plaster delivering nozzle, a gear wheel sur-
- rounding the nozzle and journaled thereon, a scraper carried by the gear wheel and located alongside the nozzle, and means for 30 rotating the scraper.
- 25 18. In a plastering machine, the combination with a support, of a rotary delivery nozzle having a discharge mouth, blades mounted in the mouth of the same and means 35 for delivering plaster into the nozzle.
- 30 19. In a plastering machine, the combination with a support, of a rotary flaring delivery nozzle, rotary blades mounted on the nozzle in the discharge end thereof, and 40 means for delivering plaster to the nozzle.
- 35 20. In a plastering machine, the combination with a support, of a rotary delivery nozzle, means for rotating the nozzle, means for delivering plaster thereto, and a scraper 45 disposed alongside the discharge end of the nozzle.

In testimony whereof I have hereunto set my hand in presence of two subscribing witnesses.

WILLIAM J. RAY.
